(57) **CLAIM**

The ornamental design for a waterproof phone case, as shown and described.

DESCRIPTION

FIG. 1 is a top, front and right perspective view of a waterproof phone case showing my new design;

FIG. 2 is a left, rear and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged partial view of FIG. 1, taken from circle "9"; and,

FIG. 10 is an enlarged partial view of FIG. 2, taken from circle "10".

The broken lines illustrating features of the waterproof phone case represent portions of the article that form no part of the claimed design. The broken line circles and wavy lines included in FIGS. 1, 2, 9, and 10 are included for the purpose of illustrating the enlarged partial views and form no part of the claimed design.
